UNITED STATES PATENT OFFICE.

JOHN LEWIS BIXBY, OF ARLINGTON, MASSACHUSETTS, ASSIGNOR TO
NATHANIEL CONANT, OF BROOKLINE, MASSACHUSETTS.

ANNUNCIATOR GAS-FIXTURE.

SPECIFICATION forming part of Letters Patent No. 608,100, dated July 26, 1898.

Application filed November 26, 1897. Serial No. 659,754. (No model.)

To all whom it may concern:

Be it known that I, JOHN LEWIS BIXBY, of Arlington, in the county of Middlesex and State of Massachusetts, have invented a new and useful Annunciator Gas-Fixture, of which the following is a specification, reference being had to the accompanying drawings, making a part thereof.

My invention is the combination of the cock with an annunciator in such manner that the act of opening the cock operates the annunciator, and while its main object is to decrease the frequency of gas-poisoning due to leaving a gas-cock open but unlighted, yet another important object is to enable the quantity of gas or other fluid supplied to be determined without a meter.

In the drawings, Figure 1 is a sectional elevation of the best form of cock embodying my invention. Figs. 2 and 2^a illustrate the manner of actuating the plunger. Fig. 3 is an end elevation of the cam and its handle. Fig. 4 is a side elevation of a spigot-cock of usual construction, but fitted with wires and contacts. Figs. 5 and 6 are sections on lines 5 and 6 of Fig. 4. Figs. 7 and 8 are diagrams illustrating my invention, Fig. 7 with two wires and Fig. 8 with three wires.

In order to attain all the objects of my invention, I use a gas-cock which must be either fully opened or fully closed, for as the time during which the cock is open can be readily ascertained from the annunciator and as the capacity of the burner is a definite number of cubic feet per hour the amount of gas supplied can be readily determined without regard to a meter. Moreover, such a cock, with its valve carried by a spring-plunger, is especially adapted for combination with an annunciator, as one of the contacts can be carried by the plunger and all contacts can be covered by a cap, which is desirable, although not essential, and in addition the use of such a cock does away with all danger of that common form of accidental gas-poisoning due to accidental opening or partially opening the cock or to leaving the gas burning so low that ordinary variations of pressure in the mains will put out the light and yet leave the gas escaping.

I will therefore first describe my new gas-

cock, which in itself is a valuable feature of my invention. It consists of a body A, with the usual inlet and outlet pipe connections a and a'; but between these two connections 55 is a port a², closed by a valve a³, which is carried by plunger a⁴, whose spring a⁵ tends to keep the valve seated. The plunger is raised by a cam a⁶, which is so constructed that it will not sustain the plunger until the 60 plunger is fully raised, as will be plain from the drawings. I have shown the cam a⁶ as a cylinder with segments cut away, and this is the preferred form, as a revolution of a very few degrees is enough to allow the plunger- 65 spring to seat valve a³.

Plunger a⁴ carries terminal b, and when the plunger is not raised b is in contact with terminal b', thus connecting wires d and d', for b is the terminal of d and b' of d', and when 70 wires d and d' are connected the proper shutter or other moving part of annunciator D is moved to its position, which announces that the cock is closed, and the motion of the shutter opens the circuit through wires d and d', 75 near the annunciator, thereby preventing further flow of the current through wires d and d', and also closes the circuit near the annunciator through wires d and d², but no current flows, because wires d and d² are not 80 then connected near the cock; but when valve a³ is held from its seat the new position of plunger a⁴ connects terminal b with terminal b², and thus completes the circuit through these wires d and d², and the current 85 flows, shifting the shutter of annunciator D to its position, which announces that the cock is open, and that shifting of the annunciator opens the circuit through d and d² and closes the circuit through d and d' near the 90 annunciator; but as terminal b is not then in contact with terminal b' no current flows until plunger a⁴ is released and terminal b again brought into contact with terminal b'; but the details above adverted to are too 95 well known to require further description, for the annunciator D, with the three-wire system, to move a screen, or a shutter, or a plate, or a lever, or the like to one position when the circuit is through one pair of the 100 three wires and to another position when the circuit is through another pair of the three

wires has long been familiar to all skilled in that art.

When an ordinary spigot-cock is used in the embodiment of my invention—as, for example, in Figs. 4, 5, 6, and 7—I prefer to use only two wires *d* and *d'*, the terminal *b* of wire *d* being brought into contact with the terminal *b'* of wire *d'* when the gas is turned on. This completes a circuit through wires *d* and *d'* and sets the annunciator to announce that the cock is open, and the action of the shifting part of the annunciator breaks the circuit at the annunciator, as is usual in this well-known form of annunciator on the two-wire system. In this form of my invention the attendant who has charge of the annunciator will make regular visits to the annunciators and will learn by looking at the annunciator which of the cocks connected with it has been opened, and by shifting the shifting part of the annunciator from its position announcing that a cock has been opened to its normal position he will close the circuit at the annunciator; but if the cock still be open the circuit will still be closed at the cock and the shifting part will not remain in its normal position after he shifts it back to that position and he will know that the cock is still open, whereupon if that cock ought not to be open at that time or in that place he will at once investigate the matter.

I am aware of Patents No. 358,161, dated February 22, 1887, to McVay, and No. 491,580, dated February 14, 1893, to Milligan, and disclaim all that is shown in them, for in my invention it is essential that when the circuit is made by opening the cock it shall be au-

tomatically broken at the annunciator end of the circuit, and there is no hint or suggestion in either of the above patents as to anything of this sort.

What I claim as my invention is—

1. In combination a cock for permitting and preventing the flow of a fluid; an annunciator with means for automatically breaking the circuit; electrodes controlled by the cock to make the circuit when the cock is opened; and electric conductors connecting the electrodes of the annunciator with electrodes of the cock, substantially as described. 50

2. A cock having a passage connecting its inlet and outlet; a valve controlling that passage; a spring-plunger controlling that valve; and a cam to move the plunger and automatically hold the plunger when in its elevated position, against the force of its spring, all substantially as and for the purpose specified. 55

3. In combination a cock with a passage controlled by a spring-plunger and a cam to move the plunger against the force of its spring; an electrode carried by the plunger; a second electrode which is in contact with the plunger-electrode when the valve is closed; a third electrode which is in contact with the plunger-electrode when the valve is open; conductors for the three electrodes; and an annunciator connected by the three conductors with the three electrodes, all substantially as described. 60
